(57) **CLAIM**

The ornamental design for a camper trailer, as shown and described.

DESCRIPTION

FIG. 1 is a perspective view from the top right rear of the camper trailer;

FIG. 2 is a front elevational view thereof;

FIG. 3 is a left side elevational view thereof;

FIG. 4 is a rear elevational view thereof;

FIG. 5 is the right side elevational view thereof;

FIG. 6 is a top plan view thereof; and

FIG. 7 is a perspective view from the front right side thereof;

FIG. 8 is a top perspective view of another embodiment of the design of the camper trailer from the top rear right thereof;

FIG. 9 is a front side elevational view thereof;

FIG. 10 is a left side elevational view thereof;

FIG. 11 is a rear elevational view thereof;

FIG. 12 is the right side elevational view thereof;

FIG. 13 is a top plan view thereof; and,

FIG. 14 is a perspective view from the front right side thereof;

The broken lines illustrate portions of the camper trailer that form no part of the claimed design.
